UNITED STATES PATENT OFFICE.

AUGUST WEBER, JR., OF SCHENECTADY, NEW YORK, ASSIGNEE TO WEBER ELECTRIC COMPANY, OF SCHENECTADY, NEW YORK, A CORPORATION OF NEW YORK.

INCANDESCENT-ELECTRIC-LAMP SOCKET.

1,120,110.

Specification of Letters Patent.

Patented Dec. 8, 1914.

Application filed January 16, 1909. Serial No. 472,687.

To all whom it may concern:

Be it known that I, August Weber, Jr., a citizen of the United States, residing at Schenectady, County of Schenectady, and 5 State of New York, have invented certain new and useful Improvements in Incandescent-Electric-Lamp Sockets, of which the following is a specification.

The invention relates to such improvements and consists of the novel construction and combination of parts hereinafter described and subsequently claimed.

Reference may be had to the accompanying drawings, and the reference characters 15 marked thereon, which form a part of this specification. Similar characters refer to similar parts in the several figures therein.

Figure 1 of the drawings is a top plan view of my improved incandescent electric lamp socket. Fig. 2 is a top plan view of the same with the cap removed. Fig. 3 is a bottom plan view of the cap detached. Fig. 4 is a bottom plan view of a modified form of cap. Fig. 5 is a view in perspective of the socket without the cap, as shown in Fig. 2. Fig. 6 is a central, vertical section of the socket, taken on the plane of the broken line 6--6 in Fig. 2, with the lower portion of the socket broken away. Fig. 7 30 is a view in perspective of a broken-away portion of the cap. Fig. 8 is a similar view of a portion of the cap inverted, showing an indented portion of the cap adapted to interlock with the case-enclosed insulating base. Fig. 9 is a view similar to Fig. 6, of a modified form of socket having a cap like that shown in Fig. 4. The several figures are drawn on an enlarged scale.

The principal object of the invention is 40 to facilitate the assembling of the cap and shell-members of the case of the socket, while preventing relative rotation of said members when applied to each other in substantially any relative rotative position and 45 interlocked to increase the internal mechanism of the socket.

Other objects of the invention will appear in connection with the following description.

50 Referring to the drawings, wherein is shown a preferred form of the invention, 1, is the shell of the socket, preferably formed of sheet-metal and provided, if for a key-

socket, with the usual slot, 2, adapted to receive the shaft of the switch-key, 12, which, 55 with the switch-mechanism not shown, is mounted upon the insulating base, 13, contained within the case, and serves as a means for preventing a relative rotative movement between the shell and said insulating base.

In applying my invention to a keyless socket, the insulating base may be interconnected with the shell in any known manner to prevent a relative rotative movement 65 therebetween. The shell is provided near its upper end with a plurality of catches, 4, preferably symmetrically disposed about the periphery of the shell, and projecting outwardly therefrom. For certain purposes of the invention these catches may be of any desired form severally adapted to interlock with a seat on the cap.

I have shown as a preferred form of catch one formed by slitting the shell transversely, and outwardly displacing a portion of the body of the shell at the upper side of said slit, thereby forming a downwardly and outwardly inclined catch with a cut-metal edge. One of the catches, 4, is 75 preferably located adjacent to the slot, 2, which may be the key-slot or a slot formed especially for the purpose of rendering the shell compressible. The cap, 3, which is 80 also preferably formed of sheet-metal, is 85 adapted to telescopically receive within its lower end the upper end of the shell, and is provided with a continuous seat, 5, extending around its inner periphery adapted to receive and interlock with the several 90 catches, 4, in any relative rotative position of the shell and cap. The seat, 5, is formed by a ledge or offset, 6, formed by bending an annular portion of the body of the cap into a plane perpendicular to the axis of 95 the cap, making the lower end of the cap substantially Z-shaped in cross-section, said ledge, 6, being adapted to be engaged by the cut-metal edges of the catches, 4, to lock the cap and shell together to prevent a relative movement of separation thereof. The lower end, 7, of the cap is adapted to ride over the inclined surfaces of the catches, 4, until the ledge, 6, reaches the lower end of the respective catches, whereupon the parts 100 interlock with a snap-action.

The cap and shell are shown in the drawings as being of substantially the same diameter, but it is to be understood that the shell may be made larger than the cap, and vice versa.

shell can thus be assembled or applied to one another by a simple telescopic movement in any relative rotative position.

As a means for preventing a relative rotative movement between the cap and shell when applied to each other, and interlocked in any one of many relative rotative positions to incase the internal mechanism of the socket, I have shown the insulating base provided on its outer end with a plurality of notches or seats, 14, and the shell, 1, cut away opposite said notches, as shown at, 15, to afford free access thereto, and I have formed upon the cap, 3, which is made of sheet-metal, a plurality of inward projections adapted to enter certain of the notches or seats, 14, in any of the many relative rotative positions in which the cap and shell may be interlocked.

As shown in Figs. 1, 2, 3, 5, 6 and 8, the inward projections, 16, are formed by inwardly displacing portions of the cap-wall, said displaced portions being adapted to pass freely through the cut-away portions, 15, of the shell.

As shown in Figs. 4 and 9, the inward projections, 17, are formed by the introverted ends of a yoke-piece, 18, fixed to the cap, which ends, 17, are adapted to enter the notches, 14, in the insulating base 13. In the form of my invention illustrated in Figs. 4 and 9, it is unnecessary to cut away the shell opposite the notches, 14, in the insulating base.

In the form of my invention illustrated in the other figures of the drawings, as much of the outer end of the shell may be removed as desired to afford free access to the notches, 14.

In both forms of my invention illustrated, the insulating lining, 19, for the cap is secured within the cap by engagement of its outer peripheral edge with the inwardly projecting members, which are adapted to enter the notches in the insulating base to prevent relative rotation of the shell and cap.

I do not wish to be limited to the particular manner of interconnecting the insulating base, both with the cap and with the shell, as my invention contemplates the use of any known means for interconnecting the cap with the insulating base independently of the shell, and for interconnecting the shell and insulating base independently of the cap, whereby the insulating base constitutes the indirect means for interconnecting the cap and shell so as to prevent a relative rotative movement therebetween.

What I claim as new and desire to secure by Letters Patent is—

1. In an incandescent electric lamp-socket, and in combination, a case comprising a shell and a cap; and a case-inclosed member, said case-inclosed member and shell

having interengaging means for preventing relative rotation, and said case-inclosed member and cap having other interengaging means for preventing relative rotation, said shell and cap having means whereby they are adapted to interlock with one another to prevent separation independently of said case-inclosed member.

2. In an incandescent electric lamp-socket, and in combination, a case comprising a shell and a cap having means whereby they are adapted to automatically interlock with one another when telescopically assembled; and a case-inclosed member, said cap, shell and case-inclosed member having means whereby said case-inclosed member automatically interlocks against rotation with each of said cap and shell independently of the other as the parts are assembled.

3. In an incandescent electric lamp-socket, and in combination, a case comprising a shell and a cap; and a case-inclosed member, said case-inclosed member and shell having automatically interengaging means, and said case-inclosed member and cap having other automatically interengaging means.

4. An incandescent electric lamp-socket having a case formed by shell and cap members, and a member inclosed by said case, and having said case-members interconnected indirectly through the medium of said case-inclosed member to prevent rotation of any of said members relatively to the others, said shell and cap having means whereby they are adapted to automatically interlock directly with one another to prevent separation.

5. In an incandescent electric lamp socket, and in combination, a sheet-metal shell, an insulating base contained within, and non-rotatively connected with, said shell, and provided on its outer end with a plurality of notches; and a cap adapted to telescopically receive said shell, said cap and shell having automatically interlocking means for preventing a telescopic movement of separation of one from the other, and said cap having means adapted to engage the notched portion of said base.

6. In an incandescent electric lamp-socket, and in combination, a sheet-metal shell; an insulating base contained within said shell, provided on its outer end with a plurality of openings, said shell and base having interengaging means to prevent relative rotation; and a cap adapted to telescopically receive said shell, said cap and shell having automatically interlocking means for preventing a telescopic movement of separation of one from the other, and said cap having means adapted to enter said openings in the base.

7. In an incandescent electric lamp-socket and in combination, case-members comprising a shell and a cap having means whereby

they are adapted to interlock against separation in substantially any relative rotary position, and a case-inclosed member, said case-inclosed member and one of said case-members having means whereby they are adapted to interlock against rotation, and said case-inclosed member and the other case-member having means whereby they are adapted to

interlock against rotation in substantially any relative rotary position. 10

In testimony whereof, I have hereunto set my hand this 11th day of January, 1909.

AUGUST WEBER, JR.
